INTERRUPTING UNIT FOR ELECTRIC
CIRCUIT BREAKERSCyril W. Driver, Secane, Pa., assignor to General
Electric Company, a corporation of New York

Application January 14, 1952, Serial No. 266,334

11 Claims. (Cl. 200—148)

This invention relates to interrupting units for electric circuit breakers and, more particularly, to an arc chute having a corrugated arcing passage formed within a laminated stack of insulating plates for use in conjunction with fluid blast circuit breakers.

A blast of fluid, such as liquid or gas, supplied to the arc chute of a circuit breaker may result in wasteful leakage of fluid through the opening in the wall of the chute through which the movable contacts are reciprocable unless special precaution is taken to minimize such leakage. Leakage of fluid is wasteful and ejection of ionized arc gases at the blade exit from the chute also may interfere with the proper operation of the circuit breaker as an effective circuit interrupting unit.

A principal object of this invention is to provide an improved interrupting unit or arc chute for electric circuit breakers wherein provision is made for minimizing the leakage of fluid pressure therefrom through an opening in a wall thereop through which a movable contact is reciprocable.

Another object of this invention is to provide an improved circuit breaker arc chute comprising a plurality of stacked plates of insulating material configured and arranged so as to form an arcing passage having an arcing region generally of trapezoidal cross section and another region of a generally rectangular cross section, the region of rectangular cross section being adapted to receive therethrough a movable blade-type contact with relatively close clearance.

Still another object of this invention is to provide an improved arc chute for an electric circuit breaker which is provided with a convergent wall arcing region near one extremity thereof which progressively modifies to an constricted region of turbulence near the other extremity thereof, the restricted region terminating in a chute opening through which the movable contact is reciprocable.

According to the invention, a plurality of notched plates of insulating material are stacked together in such a way that the notches collectively form three sides of a convergent arc passage, the fourth side of which comprises a bottom closure plate of the arc chute. The notches in the plates at one end of the chamber are trapezoidal in cross section, but toward the other end thereof the notches graduate to a rectangular cross section, a movable contact of correspondingly rectangular cross section being reciprocable in said passage and being of such size as sub-

stantially to block the exit of rectangular cross section so as to minimize the leakage of gas blast products from said chute. According to a further feature of the invention, a plurality of pairs of spaced nozzle half-plates having projections thereon are arranged with the projecting portions of the half-plates of each pair cooperating in spaced relation so as to constitute a converging-diverging nozzle with each pair of these nozzle half-plates interposed between the aforesaid adjacent notched plates so as to form a plurality of gas blast nozzles leading from a blast supply conduit and exhausting through the arc chute to atmosphere.

The invention will be better understood from the following description taken in conjunction with the accompanying drawing, in which Fig. 1 is a side view of an interrupting unit of a circuit breaker embodying the invention; Fig. 2 is an end view of a baffle stack forming the internal structure of an arc chute constructed according to the invention; Fig. 3 is a bottom view of this baffle stack; and Fig. 4 is a perspective view of the baffle stack showing certain of the plates thereof exploded for disclosing the configuration of such constituent parts.

With reference to Fig. 1, the numeral 1 represents a fixed finger-type contact which is disposed for clamping cooperation about the tip of a reciprocable flat-blade sickle-type movable contact 2. Contact 2 is mounted at its lower extremity, which is not shown, about a fixed pivot which preferably is secured to the blast pipe 3 constructed of insulating material while a blast valve, not shown, controls the flow of arc-extinguishing fluid through pipe 3. Of course, suitable mechanical means for operating the sickle-type contact 2 and the blast valve would be provided. Since these parts form no part of the present invention, they have been omitted from the drawing for the sake of simplicity. Constituting a part of the fixed contact 1 is a first terminal, while correspondingly suitable means, not shown, would be used for electrically connecting the movable contact 2 to a second terminal of the circuit breaker. A resistance 4 may be connected to the first terminal as indicated in the drawing. Secured to the upper end of the blast pipe 3 is the interrupting unit or arc chute generally designated by the numeral 5. Interrupting unit 5 is connected to the blast pipe 3 by an appropriate packing gland arrangement 6 shown secured to the chute structure by bolts 7. Support for each unit 5 is provided in the form of a pair of horizontally dis-

3

posed supporting arms 8, which are mounted on a suitable frame structure, not shown.

Since in most cases it would be desirable to arrange a resistor for connection in parallel with the contacts of the interrupter, a resistor probe 9, which emerges from the side of the arc chute structure, is indicated in the drawings. Thus, with one terminal of the resistor 4 connected to the terminal of contact 1, and with the other terminal thereof connected to the resistor probe 9, the resistor 4 would be placed in the circuit in shunt with the arc drawn by contacts 1 and 2, and, in the event that an arc restrikes to the probe 9, the resistor 4 would be in series with such a restruck arc. The effect of the resistor is to limit the magnitude of the arc current and to prevent re-establishment of the arc in known manner, as is set forth in U. S. Patent 2,284,842 to Prince et al. which is assigned to the assignee of this invention.

As is best seen in Fig. 4, the laminated internal structure of the interrupting unit 5 comprises a plurality of notched plates of insulating material designated by the letter A, together with a plurality of pairs of half-nozzle plates designated by the letters B and B'. As will be obvious from the exploded section of Fig. 4, nozzle half-plates B, B' are arranged in pairs with the enlarged ends C, C' of each pair in spaced relation to constitute a nozzle throat designated by the letter y in the drawings. It will also be obvious from Fig. 4 that the notches in the plates A at the right-hand end of the unit are trapezoidal in cross section, the smaller base of which is the length y, while the larger base portion is of length x. In the stack of notched plates, the notch dimension or width x becomes progressively smaller as progression is made from right to left, as indicated at x', in Fig. 2, so that finally the larger base portion of the trapezoidally shaped notch has diminished so as to become equal to the smaller base y as is designated in Figs. 2, 3 and 4, and therefore the notch becomes rectangular. By this means, the arcing passage generally designated by the numeral 10 is characterized by a relatively wide blasting zone 10a at the right-hand end thereof adjacent the blast pipe 3 and with a diminished constricted cross section zone 10b at the left-hand end thereof. Because the interrupting arc invariably is extinguished in the wide blasting zone 10a, and blast cut-off occurs before the blade tip emerges from the arc chute, it will be understood that the blast carries substantially all the ionized products of arcing upwardly through the nozzle plates to exhaust through the top of the chute, and that a negligible minimum of ionized gases passes out from the chute end in the wake of the tip of the movable contact 2 as it moves to its open dotted position, inasmuch as the rectangular exit aperture 11 in the closure plate 12 has but small clearance about the blade 2. Such escape of the gases is minimized by the impedance to free flow of gas offered by the inwardly stepped edges of the notches as best seen in Fig. 2, which set up turbulence in this region of diminishing blade clearance in the arc passage.

It will also be understood from Figs. 3 and 4 that the spacing between the lower extremities of the nozzle half-plates designated by the letter z is larger than the corresponding base dimension x of the notches in the plates A, so that a plurality of side pockets 10' are defined along the passage 10, which aid by increasing the above-mentioned turbulence. Thus, the passage 10 pos-

4

sesses corrugated side walls which constitute guide channels for the blast as well as a sort of labyrinth fluid seal for minimizing the escape of fluid from around the blade 2 during circuit interrupting operations. Blast fluid is supplied to the arc chute 10 from the conduit 3 through an opening in the bottom closure wall 13, which wall is best indicated in Fig. 1.

As is best shown in Fig. 4, an end plate 14 is used to cover the right-hand surface of the interrupting unit; and, likewise, fiber coverings mainly constituted by the walls of the box-like arc chute, as shown in Fig. 1, are provided for the other surfaces of the laminated structure except for the top portion thereof which, as already explained, must be open for exhausting the ionized products of an interrupting operation to atmosphere. The plates comprising the unit 5 are maintained in position by any suitable means, such as the through-bolts 15. As in the aforesaid Prince et al. patent, the upper edge of the movable contact blade is in close proximity to the baffle edges constituted by the y dimension of the notched plates, as is indicated best in Fig. 2, in which the blade section is shown as a dotted rectangle.

While I have shown and described a particular embodiment of the invention, I do not wish to be limited thereto and intend in the appended claims to cover all such changes and modifications as fall within the true spirit and scope of the invention.

What I claim as new and desire to secure by Letters Patent of the United States is:

1. An electric circuit interrupter comprising an arcing passage, a pair of relatively movable contacts arranged to separate in said passage, one of said contacts being reciprocable along the length of said passage and out from an end of said passage, means including an inlet to said passage for supplying a blast of arc-extinguishing fluid thereto in a direction transverse to the direction of movement of said reciprocable contact, outlet means exhausting from said passage disposed opposite from said inlet, said passage having opposed side walls extending in the general direction of said blast from said inlet to said outlet means, the space between said side walls forming the width of said passage, said side walls tapering gradually along the length of said passage from said inlet toward said end thereby forming a passage of tapering width converging toward said end and having at its converging end a constricted exit aperture closely surrounding said reciprocable contact, whereby said reciprocable contact substantially blocks escape of arc-extinguishing fluid from said exit aperture during arc-extinguishing operation.

2. An electric circuit interrupter comprising an arcing chamber, a pair of relatively movable contacts arranged to separate in said chamber, one of said contacts being reciprocably movable in an opening through a wall of said chamber, means including an inlet passage to said chamber for supplying a blast of fluid thereto in a direction transverse to the direction of movement of a movable one of said contacts, outlet means leading from said chamber and disposed in a wall thereof opposite from said inlet passage, the walls of said chamber being configured to define an arcing space adjacent said inlet passage which is substantially trapezoidal in cross section and to define a constricted region adjacent said opening which is substantially rectangular in cross section, said one contact being substantially rec-

tangular in cross section and being of such size as substantially to fill said constricted region.

3. An electric circuit interrupter comprising an arcing chamber, a pair of relatively movable contacts arranged to separate in said chamber, one of said contacts being reciprocably movable in an opening through a wall of said chamber, means including an inlet passage to said chamber for supplying a blast of fluid thereto in a direction transverse to the direction of movement of a movable one of said contacts, outlet means leading from said chamber and disposed in a wall thereof opposite from said inlet passage, the walls of said chamber being configured to define an arcing space adjacent said inlet passage which is substantially trapezoidal in cross section and which is disposed with its longer base dimension adjacent said inlet passage and with its shorter base dimension adjacent said outlet means, the region of said chamber adjacent said opening being substantially rectangular in cross section with one dimension substantially equal to said shorter base dimension.

4. An electric circuit interrupter comprising an arcing chamber, a pair of relatively movable contacts arranged to separate in said chamber, one of said contacts being reciprocably movable in an opening through a wall of said chamber, means including an inlet passage for said chamber for supplying a blast of fluid thereto in a direction transverse to the direction of movement of a movable one of said contacts, outlet means leading from said chamber and disposed in a wall thereof opposite from said inlet passage, the walls of said chamber being configured to define an arcing space adjacent said inlet passage which is substantially trapezoidal in cross section and which is disposed with its longer base dimension adjacent said inlet passage and with its shorter base dimension adjacent said outlet means, the region of said chamber adjacent said opening being substantially rectangular in cross section with one dimension substantially equal to said shorter base dimension, the portion of said chamber between said arcing space and the portion thereof which is rectangular in cross section being trapezoidal in cross section, the difference in length of the base dimensions of a cross section of said chamber being substantially proportional to the distance thereof from said opening.

5. An electric circuit breaker comprising a plurality of notched plates of insulating material, said notched plates being stacked with the notched portions thereof forming an arcing chamber open along one side thereof, a plate of insulating material disposed adjacent said chamber and forming a closure for said one side thereof, a plurality of nozzle plates each having a projecting portion, said nozzle plates being arranged in pairs with the projecting portions of the plates of each pair in spaced relation, each pair of said nozzle plates being interposed between adjacent ones of said notched plates, the spaces between the projecting portions of said nozzle plates constituting a plurality of nozzles leading from said passage, means including an inlet in said closure for supplying a blast of fluid to said chamber, and a pair of relatively movable contacts arranged to separate in said chamber, one of said contacts being reciprocably movable through an end of said chamber remote from said inlet, the notches in said notched plates being substantially trapezoidal in shape in the region of said inlet and being substantially rectangular in shape at said end of said chamber remote from said inlet.

6. An electric circuit breaker comprising a plu-

rality of notched plates of insulating material, said notched plates being stacked with the notched portions thereof forming an arcing chamber open along one side thereof, a plate of insulating material disposed adjacent said chamber and forming a closure for said one side thereof, a plurality of nozzle plates each having a projecting portion, said nozzle plates being arranged in pairs with the projecting portions of the plates of each pair in spaced relation, each pair of said nozzle plates being interposed between adjacent ones of said notched plates, the spaces between the projecting portions of said nozzle plates constituting a plurality of nozzles leading from said passage, means including an inlet in said closure for supplying a blast of fluid to said chamber, and a pair of relatively movable contacts arranged to separate in said chamber, one of said contacts being reciprocably movable through an end of said chamber remote from said inlet, the notches in said notched plates being substantially trapezoidal in shape in the region of said inlet and being substantially rectangular in shape at said end of said chamber remote from said inlet, the longer base dimension of said trapezoidal notches being on the side of said chamber adjacent said closure and the shorter base dimension thereof being on the side of said chamber adjacent said nozzles.

7. An electric circuit breaker comprising a plurality of notched plates of insulating material, said notched plates being stacked with the notched portions thereof forming an arcing chamber open along one side thereof, a plate of insulating material disposed adjacent said chamber and forming a closure for said one side thereof, a plurality of nozzle plates each having a projecting portion, said nozzle plates being arranged in pairs with the projecting portions of the plates of each pair in spaced relation, each pair of said nozzle plates being interposed between adjacent ones of said notched plates, the spaces between the projecting portions of said nozzle plates constituting a plurality of nozzles leading from said passage, means including an inlet in said closure for supplying a blast of fluid to said chamber, and a pair of relatively movable contacts arranged to separate in said chamber, one of said contacts being reciprocably movable through an end of said chamber remote from said inlet, the notches in said notched plates being substantially trapezoidal in shape in the region of said inlet and being substantially rectangular in shape at said end of said chamber remote from said inlet, and the longer base of said trapezoidal notches being on the side of said chamber adjacent said closure and the shorter base thereof being on the side of said chamber adjacent said nozzles, said shorter base of said trapezoidal notches being substantially equal in length to the corresponding base of said rectangular notches.

8. An electric circuit breaker comprising a plurality of notched plates of insulating material, said notched plates being stacked with the notched portions thereof forming an arcing chamber open along one side thereof, a plate of insulating material disposed adjacent said chamber and forming a closure for said one side thereof, a plurality of nozzle plates each having a projecting portion, said nozzle plates being arranged in pairs with the projecting portions of the plates of each pair in spaced relation, each pair of said nozzle plates being interposed between adjacent ones of said notched plates, the spaces between the projecting portions of said

nozzle plates constituting a plurality of nozzles leading from said passage, means including an inlet in said closure for supplying a blast of fluid to said chamber, and a pair of relatively movable contacts arranged to separate in said chamber, one of said contacts being reciprocably movable through an end of said chamber remote from said inlet, the notches in said notched plates being substantially trapezoidal in shape in the region of said inlet and being substantially rectangular in shape at said end of said chamber remote from said inlet, the longer base of said trapezoidal notches being on the side of said chamber adjacent said closure and the shorter base thereof being on the side of said chamber adjacent said nozzles, said shorter base being substantially equal to the space between the projecting portions of each pair of said nozzle plates.

9. An electric circuit breaker comprising a plurality of notched plates of insulating material, said notched plates being stacked with the notched portions thereof forming an arcing chamber open along one side thereof, a plate of insulating material disposed adjacent said chamber and forming a closure for said one side thereof, a plurality of nozzle plates each having a projecting portion, said nozzle plates being arranged in pairs with the projecting portions of the plates of each pair in spaced relation, each pair of said nozzle plates being interposed between adjacent ones of said notched plates, the spaces between said projecting portions of said nozzle plates constituting a plurality of nozzles leading from said passage, means including an inlet in said closure for supplying a blast of fluid to said chamber, and a pair of relatively movable contacts arranged to separate in said chamber, one of said contacts being reciprocably movable through an end of said chamber remote from said inlet, the notches in said notched plates being substantially trapezoidal in shape in the region of said inlet and being substantially rectangular in shape at said end of said chamber remote from said inlet, the longer base of said trapezoidal notches being on the side of said chamber adjacent said closure, and the shorter base thereof being on the side of said chamber adjacent said nozzles, said shorter base being substantially equal to the space between the projecting portions of each pair of said nozzle plates and the upstream surfaces of said projections being angularly disposed with respect to the side portions of

said notches so as to define a plurality of small cavities along the length of said arcing chamber.

10. An arc chute for a fluid cross-blast type electric circuit breaker comprising a stack of insulating plates, alternate ones of said plates being notched so as to define an arcing passageway, the intervening plates between said notched plates constituting pairs of half-plates, each pair defining a flat convergent-divergent nozzle, the notches of said notched plates having a taper less than that of the convergent portion of said nozzles whereby side walls having corrugations are defined for said passageway, a blast inlet for said passageway, an open end for said passageway through which the movable contact of said circuit breaker is withdrawn, said corrugations constituting blast guide channels adjacent said inlet and a fluid-impeding labyrinth between said open end of said passageway.

11. An electric circuit interrupter comprising an arcing passage, a pair of relatively movable contacts arranged to separate in said passage, one of said contacts being reciprocable along the length of said passage and out from an end of said passage, means including an inlet to said passage for supplying a blast of fluid thereto in a direction transverse to the direction of movement of the reciprocable contact, outlet means exhausting from said passage disposed opposite from said inlet, said passage having opposed side walls extending from said inlet to said outlet means to form an arcing space adjacent said inlet, said side walls tapering gradually along the length of said passage from said inlet toward said end so as to define a constricted exit aperture from said passage for said reciprocable contact and having corrugations therein extending transversely to the length of said passage, whereby said corrugations constitute blast guide channels adjacent said inlet and a fluid-impeding labyrinth adjacent said end.
